RELEASEABLE FLOATING VALVE

John R. Bradshaw, Duncan, Okla., assignor to
Halliburton Oil Well Cementing Company,
Duncan, Okla.

Application June 1, 1939, Serial No. 276,769

2 Claims. (Cl. 166—13)

This invention relates to floating equipment adapted for use in lowering pipe into oil wells or the like, and more particularly to an arrangement for releasably mounting a floating valve in drill pipe, casing or the like.

It is desirable, when lowering a long string of pipe into a well, to maintain a seal at or near the bottom thereof so that the mud pressure or pressure of other fluid in the well may relieve the strain on the well equipment to some extent as the result of the buoyancy of the empty string. The use of float collars or float shoes for this purpose is well known to those skilled in the art. The present invention relates to a novel construction by which the floating valve and the cage therefor may be removed from the pipe in which it is mounted should it become necessary or desirable to do so.

In accordance with the present invention, it is proposed to mount a check valve in drill pipe, casing or the like, which will permit the flow of fluid downwardly through the pipe but will normally prevent upward flow of fluid therethrough. If the apparatus of the invention is mounted in drill pipe, circulation in the normal direction used in drilling may thus be carried out without any attention being paid to the floating assembly. If, however, the drill pipe becomes stuck or if, for any reason, it is desirable to reverse the circulation of the mud fluid by pumping fluid down on the outside of the pipe and upwardly through the inside, means is provided for so manipulating the floating equipment as to permit this to be accomplished.

Accordingly, it is one object of the invention to devise a novel floating valve arrangement which may readily be released from the pipe and removed therefrom if desirable.

It is another object of the invention to devise floating equipment adapted for use in pipe and which may be released by dropping a ball and exerting pump pressure on latching means which holds the floating equipment in place.

Other objects and advantages reside in certain novel features of the arrangement and construction of parts as will be apparent from the following description taken in connection with the accompanying drawing, in which:

Figure 1 is a vertical cross-sectional view of apparatus constructed in accordance with the invention and showing the parts in the position which they occupy while fluid is being forced downwardly through the pipe;

Figure 2 is a vertical cross-sectional view of the apparatus shown in Figure 1, with the parts

shown in the position they occupy after the floating valve has been released and fluid is being forced upwardly through the pipe.

Referring to the drawing in detail, it will be seen that drill pipe is there illustrated as being made up of sections 10 and 11 connected together by a special collar 12 in which the floating valve of the present invention is mounted. The collar 12 is provided with an inner annular groove 13 within which a number of leaf springs 14 are mounted. Above the leaf springs 14, a split ring 15 of spring steel or the like is mounted, this ring being somewhat conical in shape and serving as means for latching a valve cage 16 beneath the shoulder 17 at the top of the annular groove 13.

The valve cage 16 is provided with a valve seat 18, against which the valve body 19 is adapted to fit. The valve 19 may consist of a cylinder of rubber or the like.

At its lower end, the valve cage 16 may be provided with a rubber sealing ring 20 so that when the valve 19 is closed upon the seat 18, fluid cannot flow upwardly through the collar 12.

Mounted within the collar 12 at its upper end, above the ring 17, is a releasing ring 21 secured to the collar 12 by means of shear pins 22. As illustrated in Figure 1, the lower end of the ring 21 is chamfered and extends slightly down into the ring 15. The upper end of the releasing ring 21 is provided with a seat 23 adapted to receive a ball 24 which may be dropped into the pipe when it is desired to release the floating equipment therein.

To release the floating equipment and remove it from the pipe, fluid is forced downwardly within the pipe after the ball 24 has been dropped therein until the ball 24 seats upon the ring 21 and shears the pins 22. This will be indicated at the surface by a sudden rise in pump pressure. After the pins 22 shear, the ring 21 will move downwardly forcing the split ring 15 outwardly and thus releasing the valve cage 16 from the collar 12. The direction of circulation of the mud may then be reversed as indicated by the arrows in Figure 2, and since the valve 19 will then seat within the cage, all of the valve assembly and also the releasing ring 21 and the ball 24 may be pumped out of the well.

While only one embodiment of the invention has been shown and described herein, it is obvious that various changes may be made in the construction and arrangement of parts without departing from the spirit of the invention or the scope of the annexed claims.

I claim:

1. In floating equipment for use in pipe in oil wells, a collar adapted to be made up with the pipe, a valve cage in said collar, said valve cage having a valve therein, means for latching the valve cage against upward movement in said collar, means for sealing the valve cage to said collar and means for tripping the latching means when desired to permit said valve cage and the 10 valve therein to move upwardly and out of the pipe after the pipe has been floated into the well, said latching means including a releasing ring held by shear pins to said collar and having a valve seat on its upper end and said tripping 15 means including a ball adapted to rest upon said valve seat.

2. In floating equipment for use in pipe in oil wells, a collar adapted to be made up with the pipe, a valve cage in said collar, said valve cage having a valve therein, means for latching the valve cage against upward movement in said collar, means for sealing the valve cage to said collar and means for tripping the latching means when desired to permit said valve cage and the 10 valve therein to move upwardly and out of the pipe after the pipe has been floated into the well, 15 said tripping means including a ball adapted to be dropped into the pipe to seat on a portion of said latching means and move the same when fluid pressure is exerted upon said ball.

JOHN R. BRADSHAW.
